CENTRIFUGAL PUMP

Frank B. Allen, Lower Merion Township, Montgomery County, Pa., assignor to The Allen-Sherman-Hoff Company, a corporation of Pennsylvania

Application June 4, 1929, Serial No. 368,289

2 Claims. (Cl. 103—103)

This invention relates to the art of centrifugal pumps and pumping and is particularly concerned with a new and improved apparatus for pumping liquid containing substances injurious to parts of the pumps.

Although methods and apparatus for the centrifugal pumping of liquid have been in use for a considerable period of time, they have not been utilized prior to my invention, so far as I am aware, with any marked degree of commercial success in the pumping of liquid containing substances having an injurious action on parts of the pump. For instance, attempts with which I am familiar have been made heretofore to utilize the prior art pumps and pumping methods in pumping water containing ash from coal burning furnaces. These attempts have been unsuccessful commercially for several reasons.

The ash containing water enters the spaces between the impeller and the impeller casing and causes rapid wear on the adjacent surfaces. Such wear required high maintenance cost and had the further serious difficulties that it permitted leakage of water from the high pressure chamber of the pump with a corresponding reduction in efficiency of the pump and a limitation on the effective liquid pressure obtainable at the pump discharge. This was due to the fact that the ash carrying water wore away the walls between the rotating element and the casing where close clearances were initially provided and as these parts wore more and more the clearances became greater and greater and permitted the pumped liquid to escape between the impeller and the side walls of the casing thereby decreasing the available amount of liquid pumped and also limiting the liquid pressure thereof.

Moreover, the liquid which in this manner escaped from the pump discharge penetrated on the engine side of the impeller to the adjacent bearing of the impeller shaft, and, since such liquid was under high pressure, it quickly penetrated for the full length of the bearing and rapidly cut away and otherwise injured the bearing. Furthermore, a stuffing box had to be provided which was capable of withstanding the high pressure on the liquid in the casing or the liquid could flow along the shaft and out of the casing through the stuffing box with further resultant loss in the fluid pumped and in the pressure obtainable in the pump discharge.

Despite the fact that the pump impeller and casing have been made heretofore of abrasion resisting materials the pumps so constructed have not been satisfactory commercially, so far as I

am aware, for long continued operation without more or less close attention on the part of an operator.

By my present invention, however, which involves a method of pumping that I believe is new, and by pumps suitably constructed, in what I believe to be a new and improved manner, I am enabled commercially to pump liquid carrying substances which may be of various compositions and which would have an injurious effect upon the pump parts of the prior art. Among such substances I mention ash water, sandy water, salt water and the like merely as being illustrative of this general class of materials.

My invention enables me to reduce substantially wear of or injury to the impeller and casing and bearing of a centrifugal pump; to maintain over long periods of use a very close running clearance between the casing and impeller; to construct a pump which is highly efficient initially and whose efficiency can be maintained for a long time without close personal attention; and to maintain an effective liquid pressure closely approximating the theoretically calculated pressure as deduced from the impeller peripheral speed.

For the purpose of disclosing my invention so that those skilled in the art may understand and be able to practice the same I have shown apparatus embodying my invention in the drawings accompanying and forming a part of this specification in which

Fig. 1 is a vertical sectional view through a horizontal centrifugal pump;

Fig. 2 is a vertical longitudinal cross sectional view of a vertical centrifugal pump having parts broken away; and

Fig. 3 is a chart showing the pressure head capacity curve of the impeller blades of the pump of Fig. 1.

Referring first to the modification of my invention disclosed in Fig. 1 the pump is mounted on a horizontal base 1 which is preferably of sufficient length also to constitute a base for pump driving means (not shown), for example, an electric motor suitably connected to shaft 2 of the pump. On base 1 rests a supporting body which, if desired, may be composed of two sections 2 and 3 slidably engaging the base 1 and provided with means for attaching the sections to each other.

These sections 2 and 3 are preferably composed of cast iron. Section 3 has a doubly flanged portion 4 bored to receive bearings for the shaft 2, here shown as consisting of ball-bearings, the

outer races 5 of which engage the inner surface of the portion 4 and supports ball bearings 6 which seat in inner races 7 on the shaft 2 and against the shoulder 8 thereon. Suitable adjusting screws 9 serve to adjust the bearings in the portion 4 and lock nuts 10 press the races 7 against the shoulder 8.

Section 2 consists of a cylindrical portion 11 having a flanged end 12 adapted to be attached to a correspondingly flanged part of section 3 and is bored lengthwise to receive the shaft 2 and a bearing 16 therefor. The shaft 2 is preferably provided with a sleeve 14 of bearing material to bear against the bearing 16, which consists of some suitable material such as rubber, lignum-vitæ or the like, carried by a supporting shell 17 which seats on the inner walls of the bore through cylinder 11. Preferably, the bearing 16 has recesses cut in its inner surface extending lengthwise thereof and running around the bearing in the form of rifling. Suitable packing material 18 is disposed in the bore of cylinder 11 on the engine side of the bearing 16 and together with a gland 19 constitutes a stuffing box.

The cylindrical portion 11 of section 2 is preferably formed integrally at the pump end thereof with a member 20 which constitutes the engine side plate of the impeller casing. The remainder of the impeller casing consists of a central member 21 and the intake side plate 22, these two plates 20 and 22 and intermediate member 21 being conveniently and detachably connected together by bolts inserted in open-ended notches 23 and 24 of cooperating marginal portions of the several parts. The intake side plate 22 has a central inlet opening in which is positioned a member 25 preferably provided with an inwardly flaring inlet opening, the member 25 being adapted for attachment to the side plate 22 and to an inlet pipe (not shown) in a manner similar to that just described above for the several parts of the impeller casing.

The impeller comprises a hub portion 26 suitably secured, as by a key and keyway, to the shaft 2, a disc 27, main impeller blade 28 on one side of the disc and auxiliary impeller blade 29 on the other side thereof and a centrally perforated disc 30 serving as a cover for the main impeller blade 28 and as a member through which liquid to be pumped may pass into contact with the main blade 28. The discs 27 and 30 are provided with flanged peripheral portions 31 and 32 respectively having a relatively close running clearance with adjacent portions of the intermediate casing member 21 and cooperating with adjustable wear rings 33 and 34 carried respectively by the side plates 20 and 22. The side plate 22 also carries an adjustable wear ring 35 positioned adjacent to the inlet opening of the casing to cooperate with a raised and ground or machined annular boss or land on the outer surface of the disc 30.

It will be noted that the disc 27 serves to subdivide the interior of the impeller casing into a chamber 36 between the disc 27 and engine side plate 20 and the main chamber 37 in which the main blade 28 is disposed. In a similar manner the disc 30 sub-divides the interior of the impeller casing into a chamber 38 between the intake side plate 22 and the disc 30 and the main chamber 37 in which the main blade 28 is disposed. Thus the impeller casing has three separate chambers 36, 37 and 38 of which chambers 36 and 38 communicate with chamber 37. The

size of the annular passage 39 between chambers 36 and 37 may be controlled by relative adjustment of the disc 27 and wear ring 33 while relative adjustment of the wear members 34 and 35 and disc 30 control the sizes of the annular passages 40 and 40a between the chamber 38 and chamber 37.

Chambers 36 and 38 communicate with each other through a piping connection 41 and also communicates through piping 42 with the bearing 16 in cylinder 11. Pipe connections 43 which opens into chamber 46 serves to supply liquid which is substantially free from injurious substances to the interior of the impeller casing.

The operation of the above described device is substantially as follows:

The pump driving means is energized and rotates shaft 2 and the impeller. Liquid is admitted into the casing through pipe 43 and pumped by the auxiliary impeller blade 29 into the chamber 36 under considerable head pressure applied thereto. The liquid so pumped passes through the passage 39 in the chamber 37 and also passes through conduit or pipe 41 into chamber 38 where substantially the same head pressure is created and maintained as exists in chamber 36. At the same time liquid passes through pipe 42 and proceeds through the rifling grooves in the bearing 16 back into the chamber 36. This travel is partly due to the higher pressure existing in the outer portion of chamber 36 than adjacent to the hub 26 and also by the suction created at the impeller end of the bearing 16 by the auxiliary blade 29.

When liquid to be pumped is admitted through member 25 into the casing the main impeller blade 28 pumps such liquid to the outlet opening of the casing. Inasmuch as the casing outlet opening is larger in comparison to the size of the blade 28 than is the case with the outlet opening of chamber 36 and the auxiliary blades 29, and further since the blades 29 are somewhat longer than the blades 28 and, therefore, tend to create a greater head pressure on liquid in chamber 36, the result is that the liquid in chambers 36 and 38 will be under a greater pressure than the liquid in chamber 37 and hence the liquid from these two chambers will flow into the chamber 37 against the pressure on the liquid in the latter. This flow of liquid from chambers 36 and 38 into the chamber 37 effectually prevents any liquid carrying substances injurious to the pump parts from entering the spaces between the impeller and the casing walls or penetrating to the shaft bearing. Hence liquid carrying various materials which might be injurious to the pumps heretofore constructed can be satisfactorily handled on a commercial scale by a pump embodying my invention without the ordinary troubles incident to the use of the prior art pumps.

It will be understood that in the pump above described the impeller will be hydrostatically balanced. If the pressure in chamber 36 exceeds that in chamber 38 the impeller will tend to move away from the wear ring 33 thereby enlarging the opening 39 and correspondingly closing the openings 40 and 40a. The variation in these openings will automatically vary the pressure in the two chambers and when the pressure in chamber 38 exceeds that in chamber 36 the impeller will move in the opposite direction. It will be understood that these slight movements will be permitted by the ball bearings in the portion 4 of section 3. In this manner the impeller will

tend automatically to find a position in which the pressure on opposite sides thereof from chambers 36 and 38 will be substantially equal and thus the impeller will be hydrostatically balanced. As the pressure of the auxiliary flushing liquid within the chambers 36 and 38 is substantially equal during operation of the pump, the tendency for the flushing liquid to flow into the main pumping chamber will be substantially equal at all points of communication between the main and auxiliary chambers. These points of communication are three in number, namely, the passage between the ring 33 and the portion 31 of the impeller, the passage between the ring 34 and the portion 32 of the impeller and the passage between the inner periphery of the disc 30 and the pump inlet pipe 25.

The pump shown in Fig. 2 is like the pump in Fig. 1 in many respects which concern the general construction of the impeller and casing but differs therefrom in respects incident to the changing of the horizontal pump of Fig. 1.

The shaft driving means (not shown) is carried on a plate 50 supported in any suitable manner, for example, on the walls of a sump containing liquid to be pumped. The shaft 51 extends downwardly through the plate 50 and is attached to the impeller at the lower end. A shaft housing and non-abrasive fluid reservoir 52 depends from the plate 50 carries a bearing 53 intermediate the ends of the shaft and is secured to a member 54 corresponding to cylinder 11 of Fig. 1 in which cylinder 54 and a bearing 55 are disposed, this bearing 55 being constructed of suitable material such as those previously described and preferably suitably rifled but with a pipe 56 corresponding to pipe 42 of Fig. 1 leading into the bearing 55 intermediate its ends. A pipe 57 serves to bring liquid substantially free of pump injuring substances into the housing 52 and a pipe 58 serves to withdraw liquid from the lower portion of casing 52 and conduct it into the impeller housing through a communicating pipe corresponding to pipe 43 of Fig. 1.

At the intake side of the impeller casing an inlet pipe 59 is provided at the inlet end of which an annular conduit 60 is disposed provided with a plurality of nozzle openings 61 through which conduit and openings fluid under pressure may be discharged to dislodge any pieces of solids which might clog the pipe 59 and to insure the presence of the proper amount of diluting liquid for satisfactory pumping of the solids. A steadyng support 62 is associated with the pipe 59.

In Fig. 3 I have shown a chart which illustrates the characteristic curves of the pump just described. The head pressure capacity curve of the blades 29 is shown as curve A, the pump being so designed that the blades 29 will operate at approximately the point X on this curve. A corresponding characteristic curve of the blades 28 is shown as curve B with the blade and pump being designed to operate at substantially the point Y on this curve. The difference in vertical

distance between the point X and Y indicates the excess of head pressure on liquid pumped by the blades 29 over that pumped by the blades 28. This chart shows why the liquid in chambers 36 and 38 will flow into chamber 37.

Having thus described my invention so that those skilled in the art may be enabled to practice the same what I desire to secure by Letters Patent is defined in what is claimed, it being understood that many changes may be made in the described method and apparatus without departing from the spirit and scope of the invention.

What is claimed is:

1. In combination in a centrifugal pump of the class described, a pump casing, a shaft bearing having an end opening into said casing, a liquid reservoir disposed at the opposite end of said bearing, said opposite end of said bearing opening into said reservoir, a shaft supported by said bearing, an impeller disposed in said casing and mounted on said shaft for rotation therewith, said impeller having side discs adapted to divide said housing into a central main chamber and auxiliary side chambers and having main impeller blades disposed in the main chamber and auxiliary impeller blades disposed in the auxiliary side chamber on the side of the housing into which said shaft bearing opens, a fluid conducting passage extending from said reservoir to said auxiliary chamber into which said bearing opens at a point adjacent the bearing, a fluid conducting conduit extending from said last mentioned auxiliary chamber at a point adjacent the periphery of said auxiliary impeller to said bearing at a point between the ends of the bearing, a fluid conducting conduit extending from said last mentioned auxiliary chamber to the auxiliary chamber on the opposite side of said main chamber, and means for conducting non-abrasive fluid from a source of supply to said reservoir.

2. In combination in a centrifugal pump of the class described, a pump casing, a shaft bearing having an end opening into said casing, a shaft supported by said bearing, an impeller disposed in said casing and mounted upon said shaft for rotation therewith, said impeller having side discs adapted to divide said housing into a central main chamber and auxiliary side chambers and having main impeller blades disposed in the main chamber and auxiliary impeller blades disposed in the auxiliary side chamber on the side of the housing into which said shaft bearing opens, a fluid conducting conduit extending from said last mentioned auxiliary chamber at a point adjacent the periphery of said auxiliary impeller to said bearing, a fluid conducting conduit extending from said last mentioned auxiliary chamber adjacent the periphery of said auxiliary impeller to the auxiliary chamber on the opposite side of said main chamber, and means for conducting non-abrasive fluid from a source of supply to said auxiliary chamber into which said bearing opens.

FRANK B. ALLEN.
